DESIGN FOR A HANDKERCHIEF OR SIMILAR ARTICLE

Application filed October 22, 1932. Serial No. 45,509. Term of patent 14 years.

To all whom it may concern:

Be it known that I, VAUGHAN FLANNERY, a citizen of the United States of America, residing in New York, in the county and State of New York, have invented a new, original, and ornamental Design for a Handkerchief or Similar Article, of which the following is a specification, reference being had to the accompanying drawing, forming a part thereof.

The figure is a face view of a handkerchief showing my new design.

The motif of the design is in the arrangement of the arrows around the border of the calendar so as to symbolize time in its flight being restrained and held temporarily in check.

I claim:

The ornamental design for a handkerchief or similar article as shown.

Signed by me at New York, in the county of New York and State of New York, this 13th day of October, 1932.
